CLAIM

The ornamental design for a letterpress plate system, as shown and described.

DESCRIPTION

FIG. 1 is a perspective view of a letterpress plate system in a closed uncompressed configuration;

FIG. 2 is a top plan view of the letterpress plate system;

FIG. 3 is a bottom plan view of the letterpress plate system;

FIG. 4 is a rear elevation view of the letterpress plate system;

FIG. 5 is a front elevation view of the letterpress plate system;

FIG. 6 is a left side elevation view of the letterpress plate system;

FIG. 7 is a right side elevation view of the letterpress plate system; and,

FIG. 8 is a perspective view of the letterpress plate system in an open configuration.

The broken lines immediately adjacent to the shaded areas depict the bounds of the claimed design, while all other broken lines are directed to environment. The broken lines form no part of the claimed design.

1 Claim, 6 Drawing Sheets
